ABSTRACT: Apparatus for assembling line typecastings issuing from a plurality of typecasting machines each having a chute connected thereto for guiding said castings from the machines to a conveyor which carries the castings to an assembly table on which they are deposited between retainers at predetermined positions, each correlated with a selected typecasting machine whereby the castings from each machine are sequentially positioned in a group different from the grouped castings from other machines.

ASSEMBLY APPARATUS FOR CAST LINES OF TYPE
SUMMARY OF THE INVENTION

This invention relates to an apparatus for assembling printing line typecastings issuing from linotype or similar typecasting machines.

The apparatus of this invention comprises a support frame mounting an assembly table, a typecasting transporting means discharging at a plurality of different parts of said assembly table and connected to a plurality of typecasting machines for transporting typecastings issuing from each of said machines to a predetermined part of said assembly table, said assembly table having mounted thereon a plurality of retaining means each holding successively accumulated castings from one machine only in an aligned sequential relationship, and means for advancing each group of accumulated castings to accommodate successive receipt of additional castings from said transporting means and positioning all castings from each machine in an aligned sequential relationship.

Previously, printing line typecastings were manually gathered from each of a group of typecasting machines and then were assembled manually into printing columns or groups. On occasion, a typecasting would be mispositioned with resultant error of the material printed therefrom, or a requirement to correct the error manually if detected.

The apparatus of this invention automatically collects and assembles in correct sequence at a single work station the typecastings which issue from each of a plurality of typecasting machines. The typecastings need not be manually handled until after they have been assembled into column printing groups. Thus the services of only one person in addition to the linotype operators is required to prepare assembled groups of typecastings.

Accordingly, it is an object of this invention to provide a means for automatically assembling printing line typecastings.

It is a further object of this invention to provide a means for automatically assembling line typecastings into column printing groups as they are discharged from a plurality of typecasting machines.

Further objects of this invention will become apparent upon a reading of the invention's description.

BRIEF DESCRIPTION OF THE DRAWINGS

The preferred embodiment of this invention has been chosen for the purposes of illustration and description wherein:

FIG. 1 is a perspective view of the assembly device of this invention;

FIG. 1A is a detail perspective view of a part of the device;
 FIG. 2 is a fragmentary side elevation of the assembly device of FIG. 1;

FIG. 3 is a top plan view of the assembly table of this invention as viewed along line 3-3 of FIG. 2;

FIG. 4 is a fragmentary front elevation of the casting distribution assembly as viewed along line 4-4 of FIG. 3;

FIG. 5 is a fragmentary detail side view of a portion of the casting distribution assembly as viewed along line 5-5 of FIG. 3;

FIG. 6 is a fragmentary detail sectional view of the discharge end of the conveyor taken along line 6-6 of FIG. 3;

FIG. 7 is a fragmentary top plan view of the conveyor as viewed along line 7-7 of FIG. 2;

FIG. 8 is a detail sectional view taken along line 8-8 of FIG. 7 and showing the actuating mechanism of electrical switches used in the device;

FIG. 9 is a fragmentary sectional view of the switch actuating mechanism taken along line 9-9 of FIG. 8;

FIG. 10 is a fragmentary top plan view of the casting distribution assembly mechanism in one operating position, with parts broken away;

FIG. 11 is a fragmentary top plan view of the casting distribution assembly mechanism in another operating position;

FIG. 12 is a detail sectional view taken along line 12-12 of FIG. 10;

FIG. 13 is a fragmentary vertical sectional view of the typecasting shifting mechanism taken along line 13-13 of FIG. 12;

FIG. 14 is a fragmentary perspective view of a chute and conveyor assembly used in the device;

FIG. 15 is a fragmentary side elevation on the chute and conveyor assembly shown in FIG. 14;

FIG. 16 is a fragmentary top plan view of the conveyor and chute assemblies with parts shown in section taken along line 16-16 of FIG. 15;

FIG. 17 is a fragmentary top plan view of the chute assembly as viewed along line 17-17 of FIG. 15; and

FIG. 18 is a fragmentary elevation as viewed along line 18-18 of FIG. 17.

DESCRIPTION OF THE PREFERRED EMBODIMENT

The preferred embodiment of the device is here illustrated but is not intended to be exhaustive or to limit the invention to the precise structure disclosed. It is chosen and described in order to best explain the principles of the invention and its application and practical use to thereby enable others skilled in the art to best utilize the invention.

The line typecasting assembly device 10 of this invention consists of a chute assembly for conveying the line typecastings 11 issuing from each of several typecasting machines to a conveyor transporting them along one of a plurality of selected paths to a selected portion of an assembly table correlated with the machine which produced the casting and at which the castings from that machine are sequentially grouped as required to print a column.

CHUTE ASSEMBLY

A downwardly inclined trough or chute 12, U-shaped in cross section, is connected at its receiving end to the discharge end of a linotype or similar typecasting machine (not shown). The receiving end of chute 12 is positioned in proper position and elevation by brackets 14 which are secured to the frame of the typecasting machine. Depending upon the relative location of the typecasting machine from the line typecasting assembly device 10, chute 12 may be formed in a straight line or, as shown in FIGS. 1, 14 and 17, may contain curved sections 13. Each chute 12 has a bottom web 44 and side flanges 42. The chutes may be of one piece construction or may consist of a plurality of interfitting sections held together by a connector means 15 as shown in FIGS. 14 and 15 and which may be of any construction desired. For large printing operations which utilize a plurality of typecasting machines, a chute 12 will be connected to each section machine. Each chute 12 discharges line typecastings onto a conveyor 16.

CONVEYOR ASSEMBLY

Conveyor 16 includes a channel member 20 having a base 28 and sides 29. The channel 20 has a substantially horizontal portion 31 extending alongside one or more typecasting machines and positioned below the level of the discharge end of said machines, and an upwardly inclined portion 32 whose end preferably terminates adjacent the uppermost edge 33 of an inclined assembly table 30. The inclined portion 32 of channel member 20 includes plates 34 which are secured to its sides 29 and which preferably extend below its base 28. Inclined channel portion 32 is positioned adjacent a corner of the uppermost part of assembly table 30 by a brace 38 mounted as shown in FIG. 2 secured to an extending between the side panel 40 of the support for table 30 and a channel sideplate 34. Disposed within channel member 20 and extending longitudinally thereof are a plurality of spaced parallel partitions or guides 18. Guides 18 are mounted in spaced relation above the base 28 of channel members 20 and define spaced longitudinal passages 22 in the channel. Any convenient means may be used to support and space the guides 18, such as inverted U-shaped or arch members 36 spaced along the length of and secured to member 20 at its sides 29 and serving to suspend the guides 18.

Each chute 12 discharges into a passage 22. The side flanges 42 of the discharge end of each chute 12 lie in the same plane as and have their lower ends engaging the top edge of adjacent guides 18. The base 44 of the chute may extend into the passage 22 between the cooperating guides to terminate at approximately the level of the bottom edges of the guides 18 as shown in FIG. 15. The discharge end of chute 12 may be connected to the conveyor at guides 18 and at channel 20 in any convenient manner, as by means of a pin 25 passing through one or more brackets 26 projecting from guides 18 or channel 20 and through one or more brackets 24 carried by and projecting from the chute.

A gate member 23 is preferably provided adjacent the junction of each chute and conveyor. Gate 23 preferably consists of an L-shaped rod having an upright portion journaled to a guide 18 and a lower horizontal portion extending diagonally across the adjacent passage 22. The gate member is biased in a passage-spanning position by a spring 27, as shown in FIGS. 14, 15 and 16.

A transverse shaft 46 is journaled in sideplates 34 below the channel base at the discharge end of the inclined portion 32 of channel 20. A sprocket 48 is fixedly mounted upon shaft 46 and is so positioned between sideplates 34 that the channel base 28 is substantially tangent to the upper peripheral portion of the sprocket. A similar sprocket (not shown) is journaled at the opposite end of channel 20 rearward of the discharge ends of chutes 12. An endless metal link belt 50 is trained about said sprockets. The upper run 51 of belt 50 preferably rides upon channel base 28 and is spaced below the guides 18. Transverse lugs 52 project outwardly from the exterior face of belt 50 at selected longitudinal intervals, with the top edges of said lugs 52 along upper run 51 passing below the bottom edges of the guides 18. Although it is preferable to use a link belt, a flat belt trained about pulley members could be utilized in the alternative.

Shaft 46 has an extended end portion projecting outwardly from a sideplate 34 and upon which is mounted a drive pulley 54. The other end of shaft 46 is connected to a motor means (not shown) preferably located within support frame 39 of table 30. A shaft 58 substantially parallel to and disposed below shaft 46 is journaled to support frame 39 and mounts a driven pulley 56 upon its outwardly projecting end portion. A flexible endless drive member 60 is trained about pulleys 54 and 56.

ASSEMBLY TABLE

The assembly table 30 has an inclined top 62 which is mounted upon a supporting frame 39 preferably constituting a cabinet having side panels 40. A plurality of parallel guides 68 are positioned upon the top 62 at one end thereof and adjacent the discharge end of conveyor 16. Each table guide 68 is aligned with a conveyor guide 18. The guides 68 vary in length as can best be seen in FIG. 3, with their upper ends adjacent the ends of guides 18. Positioned across the table top 62 are substantially parallel horizontal retainer members 66. Retainers 66 are spaced apart a distance greater than the length of a typecasting 11 and are connected to a plate 70 which is mounted along the side 63 of table top 62 which is remote from guides 68. The outermost table guide 68 terminates with its lower end in an abutting right-angle relationship with the lowermost retainer 66 and may be secured thereto. The lower end of each of the remaining guides 68 likewise abuts a retainer 66, as shown in FIG. 3. Adjacent retainers 66, plate 70, and the lower part of each table guide 68 define a compartment 64 which communicates with a passage formed between adjacent table guides 68 and aligned with a passage 22 of the conveyor.

TYPECASTING DISTRIBUTION ASSEMBLY

Each table guide 68 is cut away at 74 at its lower end portion. A member 72 is located within each cutout 74, being disposed approximately midway between adjacent retainers

66, as shown in FIG. 11. Each member 72 is pivoted to a guide 68 in the plane of said guide by means of a depending pin 76 at its uppermost end. Pin 76 is journaled within a concentric bushing 78 which is disposed in an aperture 80 in the table top 62 and is carried by a plate 82 secured at the underside of the top 62 by means such as screws 64. A pin 86 depends from an intermediate part of each member 72 and passes through a slot or aperture 88 in table top 62. A disc 90 is preferably journaled on each pin 86 below table top 62. The inward face of each member 72 preferably is beveled at 73 as shown in FIGS. 10 and 11.

A plurality of spaced transverse actuators or pusher rods 92 pass through bushing 94 carried by or mounted within openings in a sideplate 96 of table top 62 proximate the members 72. The inner end of each rod 92 is slotted and fits around a part of the adjacent disc 90 and is preferably pinned thereto. A collar or retainer 98 is preferably mounted about the outer end portion of rod 92. Disposed about rod 92 and compressed between retainer 98 and side plate 96 is a biasing coil spring 100.

A substantially vertical rocker member or lever 110, preferably having diverging arms 128, is pivotally mounted intermediate the length of its arms between two support members 112 which project from the side panel 40 of table 30, as by a pivot pin 114 carried by the frame members 112 and journaled in aligned apertures (not shown) in rocker arms 128. The lower end of rocker member 110 journals a cam follower roller 116. Pulley 56 carries a concentric cylindrical or skirt portion 118 having an undulating cam-defining edge portion 120 as best shown in FIG 1A, which engages the cam follower roller 116. Spring members 124 (one shown) serve to urge cam follower roller 116 into engagement with skirt portion 118. As here shown, the spring members 124 are coil springs located above the level of pin 114 and are each connected at one end to an upper part of a rocker arm 128 and at the other end to a bolt or anchor 122, adjustably mounted on or secured to side panel 40.

A plate or carrier 126 is mounted upon and spans the spaced upper ends of arms 128 of rocker member 110. A plurality of solenoids 130 are mounted upon carrier 126. Each solenoid 130 is located adjacent the outwardly projecting end of a pusher rod 92. Each solenoid has a plunger 132 movable in a direction transverse to a rod 92 and has pivotally connected thereto at 134 a pusher lever 136 which is shiftable within a slot 138 of carrier 126 as shown in FIG. 5. A coil spring 140 preferably is connected at one end to an upstanding part 142 projecting above carrier 126 and at its other end to the pusher lever at a point 144 spaced above and laterally from the plunger pivot 134. Each solenoid 130 is connected in an electrical circuit to be controlled by a switch 144 actuated by a trip member 146 pivoted to a guide 18 adjacent the discharge end of the conveyor.

OPERATION

The device functions as follows: line typecastings 11 are discharged from the typecasting machines into the respective chutes 12 connected thereto and slide on edge by gravity into a conveyor passage and onto the driven link belt 50 whose upper run travels beneath the conveyor guides 18 of the conveyor channel member 20. As each casting is carried along in its proper passage 22 by link belt 50 between guides 18, it engages the gate 23 in that passage which serves to retain or retard advance of the casting allowing the belt 50 to slide thereunder until a transverse lug 52 of the link belt engages it. Lug 52 then pushes the typecasting 11 past gate 23 against the action of gate spring 27. During its traverse past gate 23 and through conveyor 16, the typecasting 11 remains in an upright position.

As each typecasting 11 proceeds in its passage along conveyor 16 and up the inclined portion 32 thereof, it contacts the trip member 146 of electrical switch 144 as shown in FIG 7. Switch 144 actuates the correlated solenoid 130 which

retracts its plunger 132 and shifts its pusher lever 136 from the full line position to the dotted line position in FIG. 5. This shifts the lever 136 from a position offset from the pusher rod to a position confronting the end of the pusher rod 92. During operation of the device 10, the skirt portion 118 of pulley 56 is rotated to continuously oscillate the rocker member 110 and solenoid carrier 126. If the plunger 132 of any solenoid 130 is retracted, as the rocker member 110 oscillates, the associated pusher lever 136 contacts the outer end of pusher rod 92 as shown in dotted lines in FIG. 12 and moves said rod endwise and inwardly against the action of spring 100. This movement of rod 92 swings inwardly the member 72 to the position shown in FIG. 11 thereby laterally shifting those line typecastings 11 previously assembled in the correlated compartment 64 to clear the passage leading to said compartment for receipt of the oncoming typecasting 11 whose advance had tripped the solenoid which activated the pusher rod 92. After a predetermined period of time and prior to the arrival of the typecasting 11 at the table compartment 64 the solenoid 130 is deactivated and its plunger 132 is retracted allowing pusher lever 136 to assume its normal position out of alignment with pusher rod 92 and permitting rod 92 to be urged by spring 100 to its extended position which permits pivotal member 72 to return to alignment with guide 68.

Each individual typecasting 11 discharged by conveyor 16 upon assembly table 30 slides downwardly upon the inclined table between guides 68 into engagement with a correlated retainer 66. A backup member 148 preferably projects into each compartment 64 and slides upon a retainer 66 to abut the assembled typecasting 11 in said compartment and maintain them in an upright position.

To prevent jamming between rod 92 and pusher lever 136 should the solenoid 130 be actuated while carrier 126 is at its most proximate relation to table 30, the spring 140 will yield when pusher lever 136 is pivoted by the solenoid.

It will be understood that the invention is not to be limited to the details herein given but may be modified within the scope of the appended claim.

We claim:

1. An apparatus for assembling line typecastings produced by a plurality of typecasting machines comprising:
an inclined assembly table;
means on said table defining a plurality of compartments
each for retaining assembled line typecastings in an 45

aligned sequential relationship;
means for receiving and transporting to said table individual castings discharged from said casting machines and including parts for separating those castings of one typecasting machine from those castings of another typecasting machine;

means on said table for guiding the advance of the castings from said receiving and transporting means to said compartments wherein those castings from one typecasting machine will be guided into one compartment and those castings from another typecasting machine will be guided into another compartment, said guide means including elongated spaced inclined members forming passages for receiving and guiding the castings discharged by said receiving and transporting means, said guide members being of different lengths, said compartment defining means extending transversely of said guide means and constituting spaced members projecting from the lower ends of said guide members; and

means for advancing the castings in said compartments including members pivoted to said table, each pivoted member normally aligned with one of said guide means at the end of a compartment, an actuating means in cooperation with each pivoted member for swinging the cooperating pivoted member into its associated compartment to advance the castings therein, said table having a plurality of slots, each pivoted member including a depending part projecting through a slot in the table, said pivoted member-actuating means including a rod slidable relative to said table and having one end engaging the depending part of said cooperating pivoted member and having its other end extending beyond the outline of said table, said rod being shiftable into said table from an inoperative position to cause the swinging of said cooperating pivoted member, a spring means for urging said rod to its inoperative position, a rockable member pivotally mounted to said table, means for continuously shifting said rockable member, rod-pushing means carried by said rockable member and shiftable into a position aligned with said rod to engage the other end of said rod and advance said rod into said table against said spring means incident to the shifting of said rockable member, and means for shifting said rod-pushing means into alignment with said rod.
